UNITED STATES PATENT OFFICE.

EDMUND OCUMPAUGH, OF ROCHESTER, NEW YORK, ASSIGNOR TO THE DEFIANCE MACHINE COMPANY, OF ROCHESTER, NEW YORK, A CORPORATION OF NEW YORK.

CHECK-PROTECTOR.

1,161,514.

Specification of Letters Patent. Patented Nov. 23, 1915.

Application filed January 2, 1914. Serial No. 809,803.

To all whom it may concern:

Be it known that I, EDMUND OCUMPAUGH, a citizen of the United States, residing at Rochester, in the county of Monroe and State of New York, have invented certain new and useful Improvements in Check-Protectors, of which the following is a full, clear, concise, and exact description, reference being had to the accompanying drawings, forming a part of this specification.

My invention relates to an improved form of check protector, in which desired amounts may be printed or embossed upon the check, and by my invention I preferably provide special devices for cutting or tearing the fiber of the check so that erasure of the protecting characters is practically impossible.

By my invention, I also provide a construction in which the number of working parts is reduced to a minimum and, as a result, the device is simple, durable and accurate.

The several drawings illustrating my invention are as follows: Figure 1 is a vertical sectional view through the machine taken through the axis of the type cylinder and shows the actuating devices for moving the platen or matrix into engagement with the printing characters. Fig. 2 is a sectional view of the parts shown in Fig. 1, taken along the line 2—2. Fig. 3 is a vertical sectional view through the parts of the machine through the center of the cylindrical platen or matrix and shows the type wheel, ink roller and operating lever in elevation. Fig. 4 is a top view of one form of matrix that may be employed in the machine. Fig. 5 is a sectional view of the matrix shown in Fig. 4, taken along the line 5—5. Fig. 6 is an enlarged bottom view of the platen or matrix. Fig. 7 shows in a view similar to Fig. 4 a modified form of matrix or platen. Fig. 8 is a plan view of the machine assembled with the upper part of the casing and the operating lever broken away to more clearly show the type wheel and inking roller. Fig. 9 is a detail view of devices employed to feed the check when the operating lever is released from its operated position. Fig. 10 is a detail view of devices employed for imparting a rotary motion to the platen or matrix when it is in engagement with the character in printing position. Fig. 11 is a view taken from the left of the parts shown in Fig. 10. Fig.

12 is a bottom view of the parts shown in Fig. 10 with the operating lever removed. Fig. 13 shows a sample form of check as it would appear when protected by means of the check protector shown in the drawings. Fig. 14 shows in detail view the construction of one of the printing characters.

Similar numerals refer to similar parts throughout the several views.

Referring to Figs. 1, 3 and 8, it will be observed that the casing or base 1 of the machine has projecting upwardly therefrom a bracket 2 in which the end of the horizontal shaft 3 is rigidly secured. Upon this shaft 3, there is mounted a type wheel or cylinder 4 having several portions formed into a common integral member as follows: The type cylinder 5, consisting of any desired characters which are to be used in printing or embossing the check, a detent wheel 6 which is just inside of the type cylinder, a setting cylinder 7 separated from the type cylinder 5 by a circular groove 8 engaged by the upper casing 9 which holds the type cylinder in place and presents to view only the setting cylinder 7. The remaining portion of this integral element is the setting handle or head 10. A thin washer 11 is placed upon the shaft 3 between the type cylinder and the bracket 2 to reduce wear of the parts. Immediately below the printing point of the type cylinder 5, there is located in a boss 12 formed in the base immediately below the surface 13, provided to receive the check to be protected, a cylindrical matrix or platen 14, provided with an enlarged cylindrical head 15 at its lower end. The boss 12 is counterbored at its lower end to the size of the head 14 to receive a spring 16, which is of sufficient strength to move the platen to its retracted position substantially flush with the upper surface 13 of the base 1 and to also move the operating parts to their normal position. Movement of the platen is controlled by a lever 17, pivoted at 18, between brackets extending from the boss 12, and this lever 17 is provided at its left-hand end, as shown in Fig. 1, with a screw 19, rounded at its upper end to engage the lower end of the platen 14. This screw may be adjusted so as to bring the platen into engagement with the printing or embossing characters with the desired degree of pressure when the operating mechanism is actuated. The other end of

110 105 110

the lever 17 is connected by means of a link 20 with the shorter end of an operating bell crank lever 21, which is pivoted at 22 between the brackets 23 extending rearwardly 5 from the bracket 2. The lever 21 is extended upward from its bearing and curved slightly forward and terminates in a round plate 24 to be engaged by the hand of the operator, so that downward pressure may be 10 conveniently exerted upon the lever to move the platen into engagement with the printing or embossing character that may be in printing position. The pivot rod 22 of the lever 21 is held in position in the brackets 15 23 by ears or lugs 25 projecting inwardly from the upper portion 9 of the casing, so that when this portion of the casing is in place, the lever is held in proper operating position.

20 As shown in Figs. 3 and 8, an ink roller 26 is provided so that it is in contact with the periphery of the type wheel 5, as a result of which rotation of the type wheel inks its characters as desired. The inking roller 25 26 is rotatably carried by a frame 27, pivotally mounted upon a rod 28, rigidly secured in the lower portion of the bracket 2. The frame 27 has secured to it a flat spring 29, which rests against the inside of the 30 wall of the upper part of the casing which is integrally formed with the bracket 2, and the inking roller 26 is thereby held in yielding engagement with the printing or embossing characters. The top wall of the removable casing 9 which extends over the type wheel and the inking roller is provided with an inking aperture 30 covered by a swinging shield 31, pivotally held in place by a screw 32. This screw 32 extends through the 35 removable casing 9 into the bracket 2, thereby holding the casing in place and, in turn, holding the type cylinder upon its supporting shaft and also preventing the removal of the pivot rod 22 from its supporting 40 brackets 23 and also preventing removal of the inking roller 26 from its supporting pin 28. Thus, the entire upper part of the mechanism is held together and controlled as to its assembly by the single screw 32.

50 The characters upon the indicating cylinder 7 are so arranged that the uppermost character indicates the nature of the printing character which is in its lowermost or printing position, so that by successively 55 setting the type cylinder by means of the setting head 10, so that the desired ones of the characters upon the indicating cylinder 7 appear uppermost in proper succession, the desired amount will be printed or 60 embossed upon the check inserted in the machine by successive operations of the operating lever 21. A spring 33 secured at one end to the bracket 2 is provided to engage the notches in the detent wheel 6 to hold 65 the type wheel in any position to which it

may be moved so that the lowermost character upon said wheel is always held in proper printing position relatively to the platen or matrix.

The check which is placed upon the supporting surface 13 to be protected is held in position upon a feeding roller 34 by means of two small rollers 35 rotatably mounted upon the right-hand end of the lever 36, as indicated in Figs. 3 and 8. This lever 36 is mounted upon a rod 37 extending horizontally from a bracket 38 projecting from the bracket 2. A spring 39 is provided for forcing the lever around on its supporting rod to bring the rollers 35 into 75 forcible engagement with the feeding roller 34. The lever 36 is provided with an extension 40 to the left of the supporting pivot rod 37, as seen in Figs. 3 and 8, so that this extension may be engaged by the hand of 80 the operator to move the rollers 35 upward away from the roller 34 to insert the check to be protected, against the adjustable guides 41 which are secured to the top of the base 1 in the manner indicated in Fig. 8. 90

The feeding roller 34 is rigidly secured to one end of the shaft 42 supported in a boss or web 43 formed integrally with the base 1. The other end of this shaft has rigidly secured to it a ratchet wheel 44, as indicated in Fig. 9. A spring pawl 45 is provided, said pawl being rigidly secured to the boss so as to hold the ratchet wheel and driving roller 34 in any position to which they may be moved. The right-hand end of the lever 17, as seen in Fig. 1, has formed thereon a downwardly extending portion 17a, to which the left-hand end of a spring operating pawl 46 is rigidly secured, as indicated in Fig. 9. This operating pawl 46 is so related to the ratchet wheel 44 that, when the operating lever 21 is moved downward to the position indicated in dotted lines in Fig. 1 to print or emboss the desired character upon a check, which is then in place between the feeding rollers 35 and the feeding roller 34, the spring 46 will be moved to the position indicated in dotted lines in Fig. 9. When the operating lever 21 is released, the spring 16 forces the platen or matrix 14 110 downward, thereby raising the spring 46 which serves to rotate the ratchet wheel 44 one tooth so that the spring 45 comes into engagement with the next tooth thereof. This rotation of the ratchet wheel 44 rotates 120 the feeding rollers 34 and 35 a sufficient amount to move the check along to a position to receive the next desired protecting character.

The ink used upon the inking roller 26, 125 which preferably has an outer surface of felt or other absorbent material, is indelible ink which when carried into the fiber of the check is extremely difficult, if not impossible, to remove. To provide for introduce- 130

ing the indelible ink into the fiber of the check, I find it desirable to provide the upper end of the platen or matrix 14 with a series of V-shaped concentric grooves as indicated in Figs. 4 and 5, these grooves being deep enough so as to make sharp circular cutting edges between them. The faces of the characters carried by the type wheel are originally smooth and flat so as to press the check firmly against the circular cutting edges of the platen. As a result, for any desired character, the imprint made upon the check is in the form of a plurality of concentric circles, each circle being interrupted by the outline of the character printed so that only such portions of the circles are printed as will together form the desired character and, wherever the circles are printed, they are cut nearly or quite through the fiber of the paper. It will be understood that it is not necessary in order to secure this result to have any impression of the cutting edges upon or into the faces of the printing characters carried by the type wheel. After repeatedly using the characters, it may develop that the printing faces will be marked or indented by means of the circular cutting edges upon the platen to a greater or less degree, but this will not in any way interfere with the effectiveness of the cutting of the paper of the check so as to introduce the indelible ink into it. The action then becomes one in which the fiber is slightly torn at the same time that the sharp edges cut it, but, in any event, the sharp circular edges of the platen or matrix cut the fiber in portions of circles so that the ink is carried into the fiber at the same places to produce the desired characters, as indicated in the sample check shown in Fig. 13. A great improvement is produced by this form of cutting or tearing of the fiber of the check in that the cuts or tears do not lie in the same direction and, if there is any attempt to erase the printed marks by mechanical means, regardless of what direction the erasing device may be moved, it will catch and tear certain portions of the check wherever it happens to pass transversely over one of the cuts or tears. In other words, it is impossible with any erasing device to have the erasing motion parallel to all of the cuts or tears in the check.

In order that the cutting edges upon the platen or matrix 14 may be utilized to the best advantage, I find it desirable to provide means for rotating the platen slightly for each operation of the machine. This may consist of mechanism, as indicated in Fig. 1, in which a spring pawl 47, rigidly secured to the inside of the base 1, is so disposed that its operating end is in engagement with the ratchet teeth 14^a formed in the lower end of the matrix or platen 14. As a result of this construction, when the platen is moved upward, the spring 47 slips over the teeth 14^a and, when the spring 16 returns the platen to its lower position, the spring 47 rotates the platen slightly so as to present new cutting surfaces to the next printing character. It will also appear that by reversing the direction of the teeth 14^a and correspondingly shaping the operating end of the spring pawl 47, the platen may be rotated upon its up-stroke instead of upon its down-stroke with the desirable result that just as the circular cutting edges are in engagement with the fiber of the check to make the circular cuts in it, the platen will be rotated slightly, which will give a shearing action to the cutting. Another means for accomplishing this rotating of the platen to secure the shearing action, is shown in Figs. 10, 11 and 12. In this modification, the platen 14^b is provided with ratchet teeth 48 upon its periphery, which are engaged by the pointed pin 49 carried by a lever 50, pivotally mounted at 51 upon a bracket 12^a extending downward from the base 1^a of the machine. The lever 50 is held normally in the position indicated in Fig. 10 by a spring 52 and the lower end of this lever is provided with a cam surface 53 engaged by the end of the lever 17^b so that, when the platen has been moved nearly to its engaging position with the printing character, the cam surface 53 is engaged by the end of the lever 17^b, as a result of which the lever 50 is rotated upon its pivot 51 and the pin 49 engages the ratchet teeth 48 and rotates the platen 14^b during the cutting operation.

As shown in Figs. 1, 3 and 8, the base 1 of the machine is open at the bottom and this opening is closed normally by means of a plate 54 provided with an upwardly extending guide tube 55, through which a screw 56 extends to secure the plate to the bracket 12. Inwardly extending lugs formed around the lower edge of the base form a seat for the plate 54, which preferably has secured to its outer surface a layer of soft material 57, such as felt, so that the machine will not injure surfaces upon which it may rest.

While I have described the platen or matrix as provided with circular cutting edges, it will be understood that I do not limit my invention to this particular form of cutting edges, as I may employ other forms, as, for example, the one indicated in Fig. 7, in which the platen 14^c is shown as provided with straight parallel cutting edges extending in two directions, which may be set in the machine so as to extend in any desired directions. It is obvious that the platen may be equipped, if desired, with but one of these sets of parallel straight cutting edges and with this form of device it is preferable to omit the mechanism for rotating the

platens, so that the cutting edges will always occupy the same position angularly of the base of the machine and thus register with any indentations that may be made in the 5 faces of the printing characters. If preferred, with this construction a keyway 14^d may be provided in the platen or matrix 14^c to prevent rotation of the same.

Certain of the printing characters which 10 it is sometimes desirable to use, as for example, the star or asterisk, have such an outline and position of printing surface that when the continuous plane printing surface of the character is engaged by the circular 15 cutting edges of the platen the center of the character is cut entirely out from the paper unless precaution is taken to prevent. To provide against this, I preferably construct such printing characters as indicated in Fig. 20 14, in which an enlarged side view of a star 60 is shown, in which the printing surface is composed of two portions 60^a and 60^b located in different planes which are substantially parallel with each other and with the plane 25 of the paper to be printed. This difference is not appreciable, being only sufficient so that when the printing portion 60^a engages the circular cutting edges on the platen to cut the paper nearly or quite through its 30 fibers, the cutting edges will be partially cut through the fibers engaging the portion 60^b of the printing surface, thus leaving some of the fiber of the paper to hold the central part of the printing character in position. 35 The construction referred to may be made either by making the printing character with all of its surface in the same plane and subsequently filing off a part of the printing surface a small amount, or these characters 40 may be cast with the desired difference in printing surfaces.

In connection with the rotation of the platen by means of the devices shown in Fig. 1, when the platen is returning from its 45 printing position, an additional result to those described above is secured, consisting in stripping the check or paper from the platen. When the platen and printing characters are brought forcibly together, there is 50 a slight wedging tendency of the paper between the cutting edges, and the rotary motion of the platen as it leaves the printing position serves to loosen the paper from the cutting edges, so that there is no tendency 55 whatever to tear the check or paper by its adhering to the platen.

Referring to the sample impression showing the result of the operation of the check protector shown in Fig. 13, it will be understood that since the printing surfaces of the printing characters are substantially plane surfaces and are inked directly, that these characters are printed upon the face of the check in substantially a solid color, 60 since the platen presses the entire surface of

the check or paper against the printing surfaces, and that the circular cuts are not apparent from the front of the check except upon close inspection. On account of the cuts extending through the paper, however, 70 the ink works into the cuts in the manner referred to above, and thus to a certain extent into the fiber of the paper, and carries the impression through the cuts to the back of the check or paper, so that the cuts appear 75 distinctly upon the back or reverse side of the check or paper printed.

It will be understood that I do not limit myself in connection with the present invention to any particular materials but, on 80 the other hand, any desired materials may be employed in making the various parts that will secure the results above indicated. For certain of the parts, as, for example, 85 the type-wheel and the parts integrally associated therewith, metal castings may be employed to advantage, although there is nothing to interfere with having the parts relatively hard, if desired. The base and casing may be formed of cast metal or may 90 be built up, as preferred, and it will be understood that I do not limit myself to the exact conformation of parts shown and described above as I may use any equivalent 95 construction without departing from the spirit of my invention.

It will be understood that my invention is operative as a check protector whether the ink is employed or not and whether the operation is a printing or an embossing 100 operation. Throughout the claims for the sake of simplicity, I shall use the term "printing" in its generic sense and shall mean thereby any operation of printing or embossing which will operate upon the 105 check to be protected to secure the results described above.

It will be understood that I do not limit myself to any particular characters upon the type wheel or cylinder, although usually 110 the figures 0 to 9 inclusive with certain other marks such as the dollar sign (\$) and the star (*) may be employed. It will at once appear that any desired indications may be employed upon the type wheel or cylinder 115 as long as corresponding indications are placed upon the indicating cylinder 7 so that the characters may be properly set in printing position.

What I claim is:

1. In a check protector, the combination of printing characters, means for bringing desired ones of said characters into printing position, a cylindrical platen disposed so that its end is adjacent to the printing character which is in the printing position, devices for bringing the end of the platen and the printing character forcibly together, the end of said platen having a plurality of concentric cutting edges formed thereon con- 120 125 130

centric with the axis of the platen, and mechanism for imparting a rotary motion to the platen during each complete printing operation.

5. 2. In a check protector, the combination of printing characters, means for bringing desired ones of said characters into printing position, a cylindrical platen disposed so that its end is adjacent to the printing character which is in the printing position, devices for bringing the end of the platen and the printing character forcibly together, the end of said platen having a plurality of concentric cutting edges formed thereon concentric with the axis of the platen, and mechanism for imparting a rotary motion to the platen when the platen and printing character are being brought forcibly together. 70
10. 3. In a check protector, the combination of a base, a bracket extending above the base, a printing unit rotatably mounted upon said bracket and comprising a printing wheel, an indicating wheel and a setting head rigidly associated together, an inking roller rotatably supported upon said bracket in engagement with said printing type wheel, a feeding roller supported by said bracket, an operating lever secured to said bracket, a platen reciprocally movable in the base, connecting devices in the base between the platen and the operating lever for moving the platen vertically when the operating lever is actuated, and a feeding 80 roller in the base below the first-named feeding roller and operated by said operating lever. 85
15. 4. In a check protector, the combination of a base, a bracket extending above the base, an integral printing unit comprising a type wheel, an indicating wheel, a setting head, and a detent wheel, a detent spring secured to said bracket and engaging said detent wheel, an inking roller rotatably supported upon said bracket in engagement with said 90 type wheel, a feeding roller supported by said bracket, an operating lever secured to said bracket, a cylindrical platen mounted in the base with its end adjacent to the under surface of the type wheel, a lever mounted in the base for moving the platen vertically against the type wheel, connecting devices between the lever in the base and the operating lever, and a feeding roller in the base coöperating with said first-named feeding roller and operated by said operating lever, said platen having a plurality of concentric cutting edges formed in its upper surface. 95
20. 5. In a check protector, the combination of a base, a bracket extending above the base, an integral printing unit comprising a type wheel, an indicating wheel, a setting head, and a detent wheel, a detent spring secured to said bracket and engaging said detent wheel, an inking roller rotatably supported upon said bracket in engagement with said 100 type wheel, a feeding roller supported by said bracket, an operating lever secured to said bracket, a cylindrical platen mounted in the base with its end adjacent to the under surface of the type wheel, a lever mounted in the base for moving the platen vertically against the type wheel, connecting devices between the lever in the base and the operating lever, and a feeding roller in the base coöperating with said first-named feeding roller and operated by said operating lever, said platen having a plurality of concentric cutting edges formed in its upper surface. 105
25. 6. In a check protector, the combination of a base, a bracket extending above the base, an integral printing unit comprising a type wheel, an indicating wheel, a setting head, and a detent wheel, a detent spring secured to said bracket and engaging said detent wheel, an inking roller rotatably supported upon said bracket in engagement with said 110 type wheel, a feeding roller supported by said bracket, an operating lever secured to said bracket, a cylindrical platen mounted in the base with its end adjacent to the under surface of the type wheel, a lever mounted in the base for moving the platen vertically against the type wheel, connecting devices between the lever in the base and the operating lever, a feeding roller in the base coöperating with said first-named feeding 115 roller and operated by said operating lever, said platen having a plurality of concentric cutting edges formed in its upper surface, and devices carried by the base and operated by the operating lever for rotating the platen during a cutting operation. 120
30. 7. In a check protector, the combination of a base, a bracket extending above the base, an integral printing unit comprising a type wheel, an indicating wheel, a setting head, and a detent wheel, a detent spring secured to said bracket and engaging said detent wheel, an inking roller rotatably supported upon said bracket in engagement with said type wheel, a feeding roller supported by said bracket, an operating lever secured to said bracket, a cylindrical platen mounted in the base with its end adjacent to the under surface of the type wheel, a lever mounted in the base for moving the platen vertically against the type wheel, connecting devices between the lever in the base and the operating lever, a feeding roller in the base coöperating with said first-named feeding 125 roller and operated by said operating lever, said platen having a plurality of concentric cutting edges formed in its upper surface, and devices carried by the base and operated by the operating lever for rotating the platen during a cutting operation. 130

- an operating lever secured to said bracket, a platen reciprocally movable in the base, connecting devices in the base between the platen and the operating lever for moving the platen vertically when the operating lever is actuated, a feeding roller in the base below the first-named feeding roller and operated by said operating lever, and a removable casing for inclosing the operating lever, the printing unit, and the inking roller, said removable casing when in place upon the base serving to prevent displacement of the parts contained within it.
9. In a check protector, the combination of a base, a bracket extending above the base, a printing unit rotatably mounted upon said bracket and comprising a printing wheel, an indicating wheel and a setting head rigidly associated together, an inking roller rotatably supported upon said bracket in engagement with said type wheel, a feeding roller supported by said bracket, an operating lever secured to said bracket, a platen reciprocally movable in the base, connecting devices in the base between the platen and the operating lever for moving the platen vertically when the operating lever is actuated, a feeding roller in the base below the first-named feeding roller and operated by said operating lever, a removable casing surrounding the type wheel, the inking roller and the lower portion of the operating lever, said casing having an aperture through it over the inking roller for inking the same, a cover for said opening, and a screw extending through the cover and the casing into said bracket to hold the cover and casing in place and thereby prevent displacement of the parts supported by the bracket inside of said casing.
10. In a check protector the combination of a base, a bracket extending upwardly from said base, a stud permanently supported in horizontal position by said bracket, a printing unit comprising a type wheel and setting hand wheel secured together and rotatably supported in horizontal position on said stud, a movable platen supported in vertical position in said base below said type wheel and capable of vertical reciprocation therein, lever mechanism for moving said platen upward against said type wheel, and a cap for inclosing said bracket and type wheel, said cap when in place preventing removal of said printing unit from said bracket and when removed permitting the ready removal of said unit from said bracket.
11. In a check protector the combination of a base, a bracket extending upwardly

from said base, a stud permanently supported in horizontal position by said bracket, a printing unit comprising a type wheel and setting hand wheel secured together and rotatably supported in horizontal position on said stud, a movable platen supported in vertical position in said base below said type wheel and capable of vertical reciprocation therein, an operating lever pivoted to said bracket and projecting upward therefrom and terminating in an enlarged flat portion for engagement with the hand of the operator, connecting mechanism between said operating lever and the lower end of said platen, and a cap for inclosing said bracket and type wheel, said cap when in place preventing removal of said printing unit from said bracket and when removed permitting the ready removal of said unit from said bracket.

12. In a check protector the combination of a base, a bracket extending upwardly from said base, a stud permanently supported in horizontal position by said bracket, a printing unit comprising a type wheel and setting hand wheel secured together and rotatably supported in horizontal position on said stud, a movable platen supported in vertical position in said base below said type wheel and capable of vertical reciprocation therein, lever mechanism for moving said platen upward against said type wheel, and a cap for inclosing said bracket and type wheel, said cap when in place preventing removal of said printing unit from said bracket and when removed permitting the ready removal of said unit from said bracket, said platen having circular cutting edges on its upper end and being freely rotatable in said base on a vertical axis extending through the printing position.

13. In a check protector the combination of a base, a printing unit rotatably supported in horizontal position by said base to bring desired printing characters into printing position, a movable platen supported in vertical position in said base below said printing unit and capable of vertical reciprocation therein, and lever mechanism for moving said platen upward against said printing unit, said platen having circular cutting edges on its upper end and being rotatable in said base on a vertical axis extending through the printing position.

In witness whereof, I hereunto subscribe my name this 25 day of October, A. D., 1913.

EDMUND OCUMPAUGH.
